Primary Examiner — Cynthia Underwood

(57) CLAIM

The ornamental design for an umbrella table revolving food server, as shown and described.

DESCRIPTION

FIG. 1 is a front view of an umbrella table revolving food server showing my new design, a rear view, a right side view and a left side view being identical to the front view.

FIG. 2 is a top view of the umbrella table revolving food server;

FIG. 3 is a bottom view of the umbrella table revolving food server; and,

FIG. 4 is a top perspective view of the umbrella table revolving food server.

The broken lines in the drawings depict environmental subject matter/or parts of the invention and form no part of the claimed design.
